(57) CLAIM

The ornamental design for a jumpsuit as shown and described.

DESCRIPTION

FIG. 1 is a front, right side perspective view of a jumpsuit showing the claimed design;

FIG. 2 is a front view thereof;

FIG. 3 is a rear view thereof;

FIG. 4 is a left side view thereof; and,

FIG. 5 is a right side view thereof.

Portions of the jumpsuit that are not shown form no part of the claimed design.

The broken lines in the figures show stitching that forms part of the claimed design.

1 Claim, 4 Drawing Sheets
